UNITED STATES PATENT OFFICE

JAMES P. RATIGAN, OF LOS ANGELES, CALIFORNIA

PUMP REIN

Application filed October 10, 1930. Serial No. 487,687.

This invention relates to pump reins, a term that applies to certain members that constitute portions of the means that connect the walking-beam with the polish rod of the pump. Sometimes the reins consist of flexible members, such as cables and at other times of rigid members such as rods. In the present instance, the rein is of the rigid type.

In pumping an oil well, for example, it is desirable that the carrier bar or polish rod grip approach the stuffing box as closely as possible when the walking-beam is at the bottom of its pumping stroke. The reason for this is that it minimizes the distance of fall of the string of sucker rods in event of breakage between the polish rod grip and the walking-beam of any of the parts that connect them, and in case of breakage, the polish rod grip drops upon the stuffing box. This tends to break the stuffing box and also tends to produce such strains in the sucker rods as to induce further breakage thereof. It is necessary at times to change the length of the pumping stroke and this is ordinarily accomplished by adjustment between the crank and the pitman end of the walking-beam.

Lengthening or shortening the pumping stroke naturally changes the relation of the carrier bar or polish rod grip to the stuffing box, with reins of a given length.

Heretofore threaded adjustments have been used on the pump reins in order that the carrier bar or polish rod grip will operate as closely as possible to the stuffing box and such adjustments are slow and laborious to make. Since two reins are employed, one on each side, the threaded adjustments also resulted in inaccuracy in the adjustment of the distances between the members that are connected with the reins thus tending to cant the polish rod to one side or the other and produce more strain on one rein than on the other.

In using the above mentioned threaded adjustments it is also necessary to employ reins of different lengths or else turn buckles to provide for different distances between the walking-beam and the stuffing boxes, in order that the carrier bar or polish rod grip

will operate as closely as possible to the stuffing box.

An object of this invention is to simplify the construction whereby the desired adjustments may be effected so as to provide for the carrier bar or polish rod grip operating as closely as possible to the stuffing box.

Another important object is to provide for relatively great adjustments in length of the reins so that a single pair of reins can be used regardless of the large number and amplitude of adjustments in the stroke of the walking-beam.

Other objects and advantages will appear in the subjoined detailed description.

The accompanying drawing illustrates the invention:

Figure 1 is a longitudinal view of a pump rein constructed in accordance with the provisions of this invention.

Figure 2 is an elevation of Fig. 1 from either side thereof.

Figure 3 is a longitudinal view, partly in vertical section, on the line indicated by 3-3 Fig. 2.

Figures 4 and 5 are horizontal sections on the lines indicated by 4-4 and 5-5, respectively, Fig. 1.

Referring to the drawing, there are provided two relatively adjustable sections, 7, 8. These sections are in telescopic relation, the member 8 sliding within the member 7. The member 7 comprises longitudinally extending spaced side bars 9 connected at intervals with cross members 10 that are provided with vertical openings 11 through which the rod 8 passes.

Each of the cross members 10 is provided on opposite sides of the openings 11 with seats or shoulders 12. In other words, each of the openings 11 along one of its transverse axes, extends from the inner face of one of the bars 9 to the inner face of the other bar 9, and the upper portion of each opening, along another transverse axis thereof, is reduced in diameter by reason of the presence of the shoulders 12. Still another way of stating this construction is that the cross members 10 are provided, adjacent to the bars 9, with sockets 13, the lower ends of which are consti-

tuted by the shoulders 12. These shoulders 12 preferably extend aslant outwardly and downwardly for a reason that will hereinafter appear.

The bars 9 are connected at one end by a yoke 14 which is provided with an eye 15 for connecting the rein to an equalizer bar or other member by which the rein is suspended from a beam hanger. The rod 8 projects from the other end of the member 7 and is provided in the projecting end with an eye 16 by which the rein may be connected with a carrier bar or polish rod grip. The other end of the rod 8 is provided with oppositely projecting lugs 17 which are of sufficient length so as to rest on the shoulders 12, when the rod 8 is turned in order to register the lugs 17 with the sockets 13. Thus, the upper end of the rod 8 and its lugs 17 together constitute a T-head. By moving the rod 8 further into the member 7, the lugs 17 will be caused to disengage the sockets 13, whereupon the rod may be turned through an angle of 90° so as to register the lugs 17 with the portions, of the openings 11, that lie between the pair of shoulders 12 that were engaged by the lugs before said rod was turned.

In the present instance, the member 7 is provided with five pairs of shoulders 12, but it is to be understood that these pairs may be increased or diminished in number. It will be seen that the lugs 17 cannot be disengaged from the shoulders 12 without first raising the rod 8 to bring the lugs 17 out of the sockets 13.

Preferably, the underfaces of the lugs 17 or, in other words, the faces of said lugs that are adapted to engage the shoulders 12, extend aslant inwardly and upwardly so as to conform to the downwardly and outwardly slanting shoulders 12, whereby when the lugs are engaged with the shoulders, the weight of the sucker rods will tend to pull the bars 9 toward one another instead of tending to spread said bars, as might occur if the shoulders 12 and underfaces of the lugs 17 were at right angles to the longitudinal axis of the member 7.

The hereinbefore described rein operates as follows: The rein is connected between the walking-beam and the sucker rods of the pump in a manner well understood in the art relating to oil well pumping. It is to be understood that the rein will be ordinarily used in duplicate, in the customary manner, though this is not absolutely necessary.

Assuming that the reins have been connected to the walking-beam and polish rod and that it is desired to adjust the length of the reins, the polish rod will be disengaged from the rod 8 by releasing the eyes 16 from the carrier bar or polish rod grip. The rod 8 of each rein is then raised sufficiently to cause the lugs 17 to clear the sockets in which they are seated and each rod will then be

given one-quarter of a turn and then raised or lowered to decrease or increase the length of the rein as required. The rod 8, then, of each rein will be given a one-quarter turn to selectively register the lugs 17 with one of the pairs of sockets, whereupon the rod will be lowered to seat said lugs within said sockets. Then the eye 16 of each rein will be engaged with the carrier bar or polish rod grip so as to again link up the reins with the polish rod.

It will be seen that it is impossible for either of the eyes 15, 16 to become accidentally disengaged during the pumping operation. Also, because of the impossibility of the rod 8 accidentally making a quarter turn, the adjustment of the length of the rein can not accidentally change.

It is preferable to employ with this rein an equalizer bar which functions to automatically equalize the weight of the sucker rods on the reins.

From the foregoing, it will be seen that the invention provides for exceptionally rapid and arcuate adjustment of reins when the length of the pumping stroke is altered, thereby to maintain the polish rod grip in operation as close as possible to the stuffing box of the well.

I claim:

1. A pump rein comprising side bars, cross members connecting the side bars and provided with openings, shoulders on the cross members at opposite sides of openings, a member extending between the side bars and projectable through one or more of said openings, a pair of lugs on the last mentioned member for selectively seating on the shoulders, a yoke connecting the bars at one end, a connection means for the yoke, and a connection means for the last mentioned member.

2. A pump rein comprising side bars, cross members connecting the side bars and provided with openings, a member extending between the side bars and projectable through one or more of said openings and provided at one end with a T-head, pairs of shoulders in the respective openings for selective seating of the T-head, the diameter of the openings on transverse axes passing through the associated shoulders being less than the long diameter of the T-head, the diameter of the openings on transverse axes passing above the associated shoulders being greater than the long diameter of the T-head, the diameter of the openings on transverse axes passing between the associated shoulders being greater than the long diameter of the T-head, a yoke connecting the side bars at one end, a connection means for the yoke, and a connection means for the other end of the last mentioned member.

3. A pump rein including side bars, cross members connecting the side bars to provide openings, sockets for said side bars provided
